DIATHERMY APPARATUS

William Running, Detroit, Mich.

Application January 18, 1940, Serial No. 314,431

6 Claims. (Cl. 128—362)

My invention relates to a new and useful improvement in a diathermy apparatus adapted for use in treating unhealthy conditions or unbalanced states of the body through the application thereto of an electric oscillatory or vibratory current.

Another object of the invention is the provision of an apparatus of this type whereby the body or a selected portion of the body may be subjected to a high frequency induced current, plus light rays and diathermy heat waves so that a complete electrical treatment of a patient may be effected with a single apparatus.

Another object of the invention is the provision of an apparatus whereby a short wave radio frequency induction mechanism may be utilized for the purposes of treating unhealthy conditions of the human body.

Another object of the invention is the provision of an apparatus whereby high frequency induced current or heat units may be caused to pass through the body in its passing from one electromagnetic field to another.

Other objects will appear hereinafter.

It is recognized that various changes and modifications may be made in the detail of structure illustrated without departing from the spirit of the invention and it is intended that such variations and modifications shall be embraced within the scope hereof.

Forming a part of this specification is a drawing, in which,

Fig. 1 is a bottom plan view of the applicator used in the invention;

Fig. 2 is a sectional view taken on line 2—2 of Fig. 1;

Fig. 3 is a perspective view of the applicator and its cooperating terminal;

Fig. 4 is a diagrammatic view illustrating the wiring used in the invention.

As shown in the drawing, I provide a housing 61 formed from suitable insulating material and preferably of a molded composition material. Positioned within this housing 61 is an insulating housing 62 on the top 63 of which is mounted a bar 64 of insulating material. Through the tube 63 and through this bar 64 of insulating material are projecting the ends 65 and 66 of a metallic coil 67. To each of the ends 65 and 66 is secured a conductor 68 and 69, respectively, which extend through the cable 70 to a metallic terminal plug 71.

The housing is open at one side and provided at its open end with the inwardly turned flange 72. Mounted on this inwardly turned flange 55

72 is a metallic screen 73 connected by a layer of insulation 74 to a metallic screen 75. The open end of the housing is closed by the glass closure 76.

Secured to the bar 64 of insulating material and embracing the coil 67 is a coil 77 formed from glass or other transparent material, this coil being a vacuum tubing containing vapor, a suitable gas, or metallic filaments therein. A metallic terminal 78 projects inwardly at each end of the transparent coil and is electrically connected by the contacts 79 to the screen sections 73 and 75.

In the diagrammatic view I have illustrated the wiring arrangement with which the invention is used and as a part of this wiring I have utilized a rectifying unit consisting of the rectifying tubes 6 with the plates of the tubes connected to the secondary S—1 of a high voltage transformer. Positioned between the secondary S—1 and the primary P—1 of this transformer I have located a tap T—1 for lowering the voltage. A time switch 11 is provided so that the circuit may be controlled to a definite period of time so that the treatment may be carried on for a definite period of time. In the circuit there is also provided an overload relay 4, this relay being used as a safety factor for the tubes and the transformers. A delay relay 3 to allow time for the rectifying tubes to heat to a safe temperature before applying the plate voltage is also interposed in the circuit. In order to eliminate the feed-back, I have applied two fixed condensers 1 connected to the feed lines and grounded, these feed lines leading into a double pole switch 2. The circuit extends to the transformer T—3, the primary of which is grounded as at 47, and a suitable tap is interposed between the primary and the secondary of this transformer. The secondary 4 is grounded and also connected to the plates of the rectifying tube 6, the filament of which is connected to the secondary S—3 of the transformer, a tap 7 being interposed between the secondary S—3 and the primary P—3. A choke coil 8 connects to the secondary S—3 and also to the line 15 to the ammeter 38. A high ohmage resistor 16 being grounded and connected to the line leading to the resistance coil 8 and also to the fixed condenser 9, one side of which is grounded.

This structure comprises a rectifying unit for rectifying the standard A. C. to D. C. and could be substituted with a motor generator set supplying D. C. The rectifying control illustrated, however, is much preferred because of the high

voltage which may be built up and which is required in an apparatus of this kind. In connection with the rectifying device I also use an oscillating device which I will now describe.

The secondary 80 is connected by the wires 81 and 82 to the filament loop 83 which extends into the tubes 84 and 85. The grid 21 of the tube 84 is connected by the wire 28 through the grid coil 27A and the wire 26' to the grid 21' of the tube 85. The grid is connected by the wire 28 to the resistance 28a and also to the condenser 86, one side of which is grounded as at 87 which also serves to ground the resistor 88. The plate 22 of the tube 84 is connected by the wire 89 to a copper wire coil 90 which serves to form the primary of a transformer. The plate 91 of the tube 85 is connected by the wire 92 to the coil 90, this coil also being connected at its center through the radio frequency choke coil 93 to the wire 94 leading to the ammeter 38. The wires 89 and 92 are connected by the wires 95 and 96 through the condenser 97 which is grounded as at 98. A coupler 99 serves to connect the coils 101 and 102, the coil 101 being a coil within the oscillating coil 90 and the coil 102 being positioned within the output coil 103. This output coil 103 is connected at its opposite ends by the wires 104 and 105 through the condenser 106. One side of the coil 103 is connected by the wire 107 to the ammeter 108 into which is adapted the plug 71 shown in Fig. 2 which is electrically connected to the cord 70. The other side of the coil 103 is connected by the wire 110 to a metallic plate 111 embedded in a plug 112 of suitable insulating material such as rubber.

In operation when the mechanism is coupled as illustrated in the diagrammatic view, the member 111 would be located on a portion of the person's body at which location it is desired to render a treatment. The housing is then positioned on the person's body at the same location, the body B shown in the diagrammatic view being positioned between these terminals, so that the current will pass through the body and set up the desired reaction resulting from the passage through the body of an induced current of high oscillating frequency. The current would be induced from the coil 61 to the coil 77 and the screen 73 and 75 would constitute a distributing outlet. The wire 107 serves as a conductor of an induced current of radio frequency. Likewise, the wire 110 serves as a conductor of induced current of radio frequency. By leading the wire 107 to the coil 61, this induced current of radio frequency is again used to induce a current in the tube 77 which delivers an induced current of radio frequency to the screens 73 and 75. In addition to this, however, the transparent coil 77 serves as a light ray medium so that it becomes possible in the electrical treatment of diseases of persons to, simultaneously, subject the person to the desirable effects resulting from the passage of a high frequency oscillating current through the person and at the same time to the applied effects of combined light ray treatment.

The light rays obtained from the coil 77 are of the long wave band and low candle power which, combined with an oscillating current of high radio frequency induced current, makes it possible to obtain the profits of light therapy at the same time the diathermy treatments are being administered. The light rays obtained from the coil 77 can be varied depending upon the nature of specific rays desired. The nature of specified rays desired will, of course, depend

upon the patient being treated and the conditions obtaining. The light rays obtained from the coil 77 may extend from infra red to ultra violet. This would, of course, depend somewhat on the structure of the coil 77 and the gas or vapor contained within the coil. The use of different gaseous vapors to obtain light rays of different colors is well-known and commonly practiced in commerce today for lighting purposes. For instance, a tube containing the proper amount of mercury vapor would produce an indigo blue color, whereas a vapor mixture of mercury and helium will produce an ultra violet. The red rays may be obtained by gaseous mixtures which are commonly used in the standard light tubes now commercially sold "neon" tubes and the various colors between these ranges may likewise be obtained by the use of different gases or different mixtures of these gases.

In all of these light colors, the low candle power is especially developed so that danger of burning is eliminated while the other desired features resulting from the high frequency of vibration are still present.

In this way I have provided a simple, compact, inexpensive, and highly efficient mechanism whereby such a combination treatment by means of the current and the light rays may be simultaneously given.

In this way also I have provided a means which combines the therapeutic effects of standard diathermy, solartherapy, and chromotherapy. At the same time I have provided means whereby heat and light may be simultaneously administered without the undesirable effects of burning or irritation which is commonly encountered in electrotherapeutics.

What I claim as new is:

1. A diathermy apparatus of the class described, comprising: a plurality of diathermy electrodes, one of which comprises a pair of screen plates edgewise disposed and insulated from each other; a gaseous discharge tube lamp mounted behind said screen plates; means for connecting the opposite terminals of said lamp to said screen plates, one of said terminals being connected to one of said screen plates and the other of said terminals to the other of said screen plates; and an electrode adjacent said lamp having an input terminal connected thereto.

2. A diathermy apparatus of the class described, comprising: a gaseous discharge tube lamp having spaced apart terminals; an inductance element adjacent said lamp for inducing a current of high oscillating frequency therein; means for connecting said inductance element to a source of oscillating current of high frequency; a diathermy electrode embodying a pair of spaced apart screen elements positioned adjacent said lamp; means for connecting one of the terminals of said lamp to one of said screen elements; and means for connecting the other terminal of said lamp to another of said screen elements.

3. A diathermy apparatus of the class described, comprising: a diathermy electrode embodying a pair of screen plates disposed edgewise relatively to each other and spaced apart at adjacent edges; a gaseous discharge tube lamp adjacent said screen plates; a terminal on said lamp connected to one of said plates; a second terminal on said lamp connected to the other of said plates; an inductance element positioned adjacent said lamp for inducing in said lamp an

oscillating current of high frequency; and means for connecting said element to a source of oscillating current of high frequency.

4. In a diathermy apparatus of the class described, a housing open at one end; a diathermy electrode embodying a pair of screen plates disposed across the open end of said housing in edgewise relation and spaced apart at adjacent edges; a gaseous discharge tubular lamp in said housing behind said screen plates; means for connecting a terminal of said lamp to one of said plates; means for connecting another terminal of said lamp to the other of said plates; and an electrode positioned adjacent said lamp for inducing in said lamp a current of high oscillating frequency.

5. In a diathermy apparatus of the class described, a housing open at one end; a diathermy electrode embodying a pair of screen plates disposed across the open end of said housing in 20 edgewise relation and spaced apart at adjacent edges; a gaseous discharge tubular lamp in said housing behind said screen plates; means for connecting a terminal of said lamp to one of

said plates; means for connecting another terminal of said lamp to the other of said plates; an electrode positioned adjacent said lamp for inducing in said lamp a current of high oscillating frequency; and means for connecting said last named electrode to a source of current of high oscillating frequency.

6. In a diathermy apparatus of the class described embodying a plurality of diathermy electrodes, a housing; a diathermy electrode embodying a pair of screen plates positioned across one side of said housing in edgewise relation to each other and spaced apart at their adjacent edges; a gaseous discharge tube lamp positioned in said housing behind said screen plates; a terminal on said lamp connected to one of said plates; a terminal on said lamp connected to the other of said plates; an inductance element in said housing adjacent said lamp for inducing in said lamp a current of high oscillating frequency; and means for connecting said inductance element to a source of current of high oscillating frequency.
